UNITED STATES PATENT OFFICE.

WILLIAM F. ECKERT AND WILLIAM C. WHITCOMB, OF ROCHELLE, ILLINOIS, ASSIGNEES
TO GEORGE D. WHITCOMB COMPANY, A CORPORATION OF ILLINOIS.

GEARING.

1,024,562.

Specification of Letters Patent.

Patented Apr. 30, 1912.

Application filed December 27, 1910. Serial No. 599,619.

To all whom it may concern:

Be it known that we, WILLIAM F. ECKERT and WILLIAM C. WHITCOMB, citizens of the United States, and residents of Rochelle, county of Ogle, and State of Illinois, have invented certain new and useful Improvements in Gearing, of which the following is a specification, and which are illustrated in the accompanying drawings, forming a part thereof.

The invention relates to gearing, and particularly to that adapted for use upon locomotives or other vehicles operated by an explosive motor.

15 The object of the invention is to provide transmission gearing for devices of the kind described which shall be of simple and improved construction and effective in operation.

20 The invention is exemplified in the structure hereinafter described and illustrated in the accompanying drawings, in which—

Figure 1 is a plan view of a locomotive embodying the features of improvement provided by the invention, some of the parts being broken away to show the internal construction; Fig. 2 is a vertical transverse sectional view taken on the line 2—2 of Fig. 1; Figs. 3 and 4 are detail face views of certain clutch elements employed in the structure; Fig. 5 is a detail central vertical longitudinal sectional view, the plane of the section being indicated by the line 5—5 on Fig. 1; Fig. 6 is a plan sectional view taken on the line 6—6 of Fig. 5; and Fig. 7 is a detail sectional view taken on the line 7—7 of Fig. 5.

The drawings show a locomotive of a type which, though being of comparatively small size in order that it may run in restricted passages, as in the tunnels of a coal mine, is capable of developing high power and equal speed in either direction.

45 The parts of the locomotive are associated upon a suitable frame, generally designated by the numeral 10 in the drawings. This frame preferably comprises longitudinal side sill members, designated 11 and 12, and end sill members or bumpers designated 13 and 14. The frame is mounted upon wheels in the usual way, two pairs of wheels 15, 16 and 17, 18, of uniform size, being shown. The wheels of each pair are rigidly mounted upon the ends of a suitable axle,

as 19 and 20. Preferably these axles are 55 coupled, as by a sprocket chain 33, which turns over sprocket wheels 34 and 35, mounted upon the axles 19 and 20, respectively.

A motor, generally designated by the numeral 21, is mounted upon the frame 10 60 preferably adjacent one end, whereby one of the end sills or bumpers, as 13, serves as a convenient seat for the operator of the motor. As shown, the motor 21 comprises four explosive power cylinders, designated 22, 65 23, 24 and 25. The power shaft 26 of the motor is preferably located upon the longitudinal median line of the frame 10.

A pair of countershafts 27 and 28 are 70 preferably employed. These countershafts are most conveniently mounted transversely in the frame 10 adjacent that end more remote from the motor 21. One of the countershafts, as 28, has driving connection with the wheels 15, 16, and 17, 18. As shown, the 75 countershaft 28 is connected to the axle 19 by sprocket chains 29 and 30, one located adjacent each side of the frame 10. Each of the sprocket chains 29 and 30 turns over sprocket wheels 31 and 32, mounted, respectively, upon the countershaft 28 and upon the axle 19. The countershafts 27 and 28 are adapted to be operatively connected by either one of two trains of gears, as 36, 37, and 38, 39, and each of the trains of gears is 80 controlled by a clutch, as 40 and 41. As shown, the gears 36 and 38 are of different size, and are rigidly mounted upon the countershaft 27. The gears 37 and 39 are loosely mounted upon the countershaft 28, and 85 they are of proper size to intermesh with the gears 36 and 38, respectively. The clutches 40 and 41 comprise outwardly directed clutch teeth, as 42, 43, formed upon the hubs of the gears 37 and 39, and movable 90 clutch members 44, 45, splined upon the countershaft 28 at opposite sides of the gears 37, 39, and having inwardly directed clutch teeth, as 46, 47, for coöoperating with the clutch teeth, as 42, 43, formed upon the hub 95 of the adjacent gear. By means of this arrangement the movable members, as 44, 45, of the clutches are adapted to be moved in opposite directions for engagement with the coöperating member of the corresponding 100 clutch.

Preferably provision is made for shifting the movable members, as 44, 45, of the

clutches 40 and 41, simultaneously, in order that the clutches may be operated in alternation. As shown, a pair of connected yokes 49, 50, are provided. Each yoke has a bifurcated end 51, which straddles the movable member of one of the clutches, and a ring 52, loosely mounted in a circumferential groove 48 formed in the hub of the said clutch member, is provided with outwardly directed pins 52' engaged by the bifurcated end of the yoke. The yokes 49, 50, are connected by being secured to a shipper bar 53, located above the gears 37, 38, and slidably mounted for movement in a transverse direction with reference to the locomotive frame. The shipper bar 53 is operated by a lever 54, pivotally supported at 55, and extending backwardly over the motor 21 to a position within convenient reach of an attendant seated upon the bumper or end sill 13.

The power shaft 26 of the motor 21 has a beveled pinion 56 mounted upon its end. Oppositely facing beveled gears 57, 58, loosely mounted upon the countershaft 27, mesh continuously with the beveled pinion 56 upon opposite sides, whereby they are driven continuously in opposite directions whenever the motor 21 is in operation. Clutches, generally designated by the numerals 59 and 60, are provided for connecting the bevel gears 57, 58, to the countershaft 27 in alternation. Each of these clutches is of a multiple disk construction, and comprises a plurality of plates or disks 61, mounted for rotation with the corresponding bevel gear, as 57, 58, and a plurality of plates or disks 62, interposed between the plates or disks 61 and connected for rotation with the countershaft 27. Preferably the plates or disks 61, 62, of each of the clutches 59, 60, are centrally apertured, as indicated at 63, 64, and they are slidably mounted upon sleeves 65, one of which is located upon the countershaft 27 adjacent each of the gears 57, 58, and is fixed against rotation thereon, as by means of a key or feather 66.

The bevel gears 57 and 58 are each permanently connected by cap-screws 67 to a rotatable member, as 68, which turns loosely on the countershaft 27 and forms one of the end plates of the corresponding clutch 59 or 60. Each of the members 68 has a plurality of arms 69, which extend parallel with the countershaft 27, and the plates 61 of the clutches are caused to rotate with such member, by engagement of the arms 69 with peripheral notches, as 70, in the plates.

Relative rotation between the plates 62 of the clutches and the countershaft 27 is prevented by means of lugs 71 (Fig. 3) formed in the plates. These lugs enter longitudinal channels, as 72, formed in the corresponding sleeve 65. Preferably the plates 62 of the clutches are made of brass and are

freely perforated, as at 73, the perforations being filled with a soft material 74, as cork, which projects beyond the face of the plate at each side to form a wear-resisting surface. The plates 61 of the clutches are preferably made of steel and have smooth surfaces upon both sides. The surfaces of the plates 61 and 62 are normally separated to permit the gears 57 and 58 to turn independently of the countershaft 27, by springs 75, which react between the lugs 71 of alternate plates 62, the lugs 71 of the intermediate plates 62 being apertured, as indicated at 76, to receive the springs. As shown, the plates 62 each have four instant lugs 71. Two of these lugs upon each plate are provided with apertures 76, and the remaining lugs are unapertured to serve as abutments for the springs 75. In arranging the plates upon the corresponding sleeve 85 member 65, the apertured lugs 71 of adjacent plates are placed in staggered relation.

For compressing the springs 75 to bring the surfaces of the plates 61 and 62 into frictional engagement, each of the clutches, as 90 59 and 60, comprises a movable end abutment 77, and a ring 78, having outstanding trunnions 79 at opposite sides, slides upon one of the members 65 adjacent each of the end abutment members 77. Provision is 95 made for moving the end abutment members 77 of the two clutches 59, 60, in unison, whereby the clutches are operated in alternation. As shown, a pair of yoke members 80 and 81, each having a bifurcated end 100 engaging the pins or trunnions 79 of one of the rings 78, are provided. These yoke members are connected to a shipper member 82 located above the gears 57, 58, and slidably mounted for movement in a transverse direction with respect to the locomotive frame. The shipper member 82 is operated by a lever 83, pivotally mounted at 84 and extending backwardly therefrom over the motor 21.

Preferably provision is made for preventing the shifting of the clutches 40 and 41 except when the shipper member 82 is in mid position corresponding to a neutral or inoperative position of each of the clutches 115 59 and 60. The arrangement about to be described also provides for a locking of the shipper member 82 against movement except when the shipper bar 53 is in one extreme position or the other, corresponding 120 to a closed position of one of the clutches 40 and 41. As shown, a locking bolt 85, having a longitudinally sliding movement, is employed. The shipper bar 53 is provided with two notches, as 86, 87, for receiving the end of the locking bolt 85, and when the locking bolt is engaged with either one of these notches the shipper bar 53 is locked against movement. The locking bolt 85 is operated by movement of the shipper 125 130

bar 82. For this purpose a cam engagement between the shipper bar 82 and the locking bolt 85 is provided. Preferably the locking bolt 85 has a transversely extended cam slot 88, having oppositely-inclined portions 88^a and 88^b. A pin 89, carried by the shipper bar 82, runs in the cam slot 88 to shift the locking bolt when the shipper bar 82 is operated. When the shipper bar 82 is in mid position, the locking bolt 85 is withdrawn from engagement with the notches, as 86, 87, of the shipper bar 53, and this shipper bar may then be shifted by operation of the lever 54. When the shipper bar 53 has been so moved that neither of the notches 86, 87, is in register with the end of the locking bolt 85, the shipper bar 82 is locked against movement by reason of the engagement of the pin 89 upon opposite sides by the oppositely inclined portions 88^a and 88^b of the cam slot 88. This interlocking arrangement provided between the shipper bars 53 and 82 prevents a movement of the clutches 40 and 41 to change the speed at which the traction wheels of the locomotive are turned by the motor 21, except when both of the clutches 59 and 60 are open. Similarly, neither of the clutches 59 and 60 can be closed except upon one or the other of the clutches 40, 41, being first closed.

Preferably the movable parts carried by the countershafts 27 and 28, including the clutches 40, 41, and 59, 60, are inclosed within a case 90 adapted to contain a bath of oil. As shown, the cover 91 of this case serves as a sliding support for the shipper bars 53 and 82, and for the locking bolt 85. The pivots 55 and 84 upon which the shipper levers 54 and 83 are mounted are most conveniently also carried by the cover 91 of the case 90.

If desired, a pump 92 may be employed for discharging oil contained in the case 90 upon the disks 61 and 62 of the clutches 59 and 60. As shown, the pump 92 is mounted within the case 90 upon an end wall thereof, and is driven by a countershaft 93 extended through the case from end to end and connected with the power shaft 26 of the motor 21 by gears 94 and 95. Oil is raised by the pump 92 from the bottom of the case 90 through a channel 96 formed in the end wall of the case, and is delivered through a pipe 97 to a spray head 98, most clearly shown in Fig. 7 of the drawings. The spray head 98 comprises a transverse pipe, connected at its middle to the pipe 97 and having closed ends 99. A plurality of lateral discharge orifices 100 are arranged at suitable intervals along the length of the pipe 98.

The arrangement described is of such compact construction as to permit of a locomotive of great power being built of such size that it may be run within the passages of a mine originally constructed with view

to receiving only draft animals and small cars. The locomotive may be run with the same speed and power in either direction.

We claim as our invention—

1. In combination, intermediate and driven rotatable members, two trains of gears connecting said members, the gears of the two trains being relatively differently proportioned in size, a clutch controlling each train of gears, the two clutches being movable in opposite directions to engaging position, a shipper lever, connection between the shipper lever and both of the said clutches, a pair of oppositely rotating power wheels, a clutch between each of the said wheels and the said intermediate rotatable member, such two clutches being movable in opposite directions to engaging position, a second shipper lever, connection between the last named shipper lever and both of the said last named clutches, the arrangement being such that both of the said last named clutches are disengaged when the last named shipper lever is in mid position, a lock for holding the first named shipper lever against movement, and means acting on the lock operated by the second mentioned shipper lever whereby the lock is released only when the second mentioned shipper lever is in mid position.

2. In combination, intermediate and driven rotatable members, two trains of gears connecting said members, the gears of the two trains being relatively differently proportioned in size, a clutch controlling each train of gears, the two clutches being movable in opposite directions to engaging position, a shipper lever, connection between the shipper lever and both of the said clutches, a pair of oppositely rotating power wheels, a clutch between each of the said wheels and the said intermediate rotatable member, such two clutches being movable in opposite directions to engaging position, a second shipper lever, connection between the last named shipper lever and both of the said last named clutches, the arrangement being such that both of said last mentioned clutches are disengaged when the said last named shipper lever is in mid position, and interlocking connection between the two shipper levers whereby the first mentioned shipper lever is released for movement only when the second mentioned shipper lever is in mid position and the second mentioned shipper lever is released for movement only when the first mentioned shipper lever is in its extreme positions.

3. In transmission gearing, in combination, a pair of reversing clutches, a pair of speed-changing clutches, a pair of parallel longitudinally reciprocable shipper bars, one controlling the reversing clutches and the other controlling the speed changing clutches, the shipper bar controlling the

speed-changing clutches being provided with a pair of lateral notches, an oscillatable locking bolt engageable with either of the said notches, said bolt being provided with 5 a cam slot having two equal but oppositely inclined portions, and a stud mounted on the shipper bar controlling the reversing clutches running in the said cam slot.

4. In transmission gearing, in combination, a pair of reversing clutches, a pair of speed changing clutches, unitary means for operating the clutches of each pair in alternation, a lock for holding the speed changing clutches against movement, said lock being 10 controlled by the said means provided for operating the reversing clutches and the arrangement being such that said lock is released only when both of the said reversing clutches are disengaged.

20 5. In transmission gearing, in combination, a pair of reversing clutches, a pair of speed changing clutches, unitary means for operating the clutches of each pair in alternation, a lock for holding the reversing 25 clutches against movement, said lock being controlled by the said means provided for operating the speed changing clutches and the arrangement being such that said lock is released only when one of said speed changing 30 clutches is fully engaged.

6. In transmission gearing, in combination, a pair of reversing clutches, a pair of speed changing clutches, unitary means for operating the clutches of each pair in alternation, and interlocking connection between 35 the said two clutch operating means whereby the speed changing clutches are held against movement except when both of the reversing clutches are disengaged and the 40 reversing clutches are held against movement except when one of the speed changing clutches is fully engaged.

7. In transmission gearing, in combination, a power transmitting clutch, a pair of speed changing clutches, means for operating the power transmitting clutch, unitary means for operating the speed changing 45 clutches in alternation, a lock for holding the speed changing clutches against movement, said lock being controlled by the 50 said means provided for operating the power transmitting clutch and the arrangement being such that the said lock is released only when the power transmitting 55 clutch is disengaged.

8. In transmission gearing, in combina-

tion, a power transmitting clutch, a pair of speed changing clutches, means for operating the power transmitting clutch, unitary means for operating the speed changing 60 clutches in alternation, a lock for holding the power transmitting clutch against movement, said lock being controlled by the said means provided for operating the speed changing clutches and the arrangement being 65 such that said lock is released only when one of said speed changing clutches is fully engaged.

9. In transmission gearing, in combination, a power transmitting clutch, a pair of speed changing clutches, means for operating the power transmitting clutch, unitary means for operating the speed changing 70 clutches in alternation and interlocking connection between the said two clutch 75 operating means whereby the speed changing clutches are held against movement except when the power transmitting clutch is disengaged and the power transmitting clutch is held against movement except 80 when one of the speed changing clutches is fully engaged.

10. In transmission gearing, in combination, a power transmitting clutch, a pair of speed changing clutches, a pair of parallel 85 longitudinally reciprocable shipper bars, one controlling the power transmitting clutch and the other controlling the speed changing clutches, the shipper bar controlling the speed changing clutches being 90 provided with a pair of lateral notches, an oscillatable locking bolt engageable with either of the said notches, said bolt being provided with an oblique cam slot, and a stud mounted on the shipper bar controlling 95 the power transmitting clutch and running in the said cam slot.

11. In combination, a pair of clutches, a pair of parallel longitudinally reciprocable shipper bars one controlling each of the 100 clutches and one of the shipper bars being provided with a lateral notch, an oscillatable locking bolt engageable with the said notch said bolt being provided with an oblique cam slot, and a stud mounted on the 105 other shipper bar running in the said cam slot.
